AUTOMATIC DRAFT REGULATED FURNACE

Arthur D. Cole, Minneapolis, Minn.

Application March 29, 1937, Serial No. 133,587
In Canada May 21, 1934

4 Claims. (Cl. 236—15)

My invention relates to furnaces and has for an object to provide a furnace in which the draft is directly controlled in accordance with the pressure in the combustion chamber of the furnace.

5 Another object of the invention resides in providing a furnace utilizing a pressure responsive draft regulator directly subjected to the pressure within the combustion chamber of the furnace.

A still further object of the invention resides 10 in providing a draft regulator for a furnace having a fire doorway and fire door, said regulator being subjected to the pressure within the combustion chamber through the fire doorway.

Another object of the invention resides in providing a neck adapted to form an extension of 15 the doorway and to which the fire door is attached and by means of which the draft regulator is subjected to the pressure within the combustion chamber.

20 A feature of the invention resides in constructing the draft regulator with a damper and a separate pressure responsive damper control for operating the damper and in mounting the damper control on the fire door and in communication with the combustion chamber through the fire doorway.

Another object of the invention resides in providing an adjusting mechanism for the damper control whereby the action of the draft regulator may be easily and quickly varied.

30 A still further object of the invention resides in providing a furnace utilizing a stoker or other type of burner resulting in a variable fire in which the draft is maintained proper for all conditions of the fire.

35 Another object of the invention resides in providing a construction whereby the draft regulator may be brought into communication with the combustion chamber without cutting a hole through the walls of the furnace forming the combustion chamber.

40 Other objects of the invention reside in the novel combination and arrangement of parts and in the details of construction hereinafter illustrated and/or described.

45 In the drawings:

Fig. 1 is an elevational sectional view of a portion of a boiler illustrating an embodiment of my invention.

50 Fig. 2 is a plan sectional view taken on line 2—2 of Fig. 1 drawn to a larger scale and showing the parts in altered position.

Fig. 3 is an elevational sectional view taken on line 3—3 of Fig. 2 and showing the parts in the same position as in Fig. 1.

55

Fig. 4 is an elevational view of a portion of a boiler illustrating the embodiment of a modification of my invention.

Fig. 5 is an elevational sectional view of the damper control of the form of the invention shown in Fig. 4 and taken through the fire door of the boiler.

In the control of the draft for furnaces such as domestic and commercial heating plants, boilers and the like, it has heretofore been the practice to utilize a pressure responsive device which has been connected in the smoke pipe or exteriorly of the furnace and which is adapted to actuate or control the operation of a damper connected in the smoke pipe or the chimney. Such devices are not entirely accurate due to the fact that the pressure within the combustion chamber where the amount of air is to be controlled does not always correspond with the pressure in the smoke pipe since the products of combustion usually pass through tortuous passageways where heat exchange occurs before entering the smoke pipe and after leaving the combustion chamber. This is particularly true where an automatic stoker is used to fire the furnace or where an oil burner having two or more sizes of flame is utilized. Furthermore fluctuations in pressure in the smoke pipe are not always transmitted to the combustion chamber so that needless variation of the damper is procured. The present invention overcomes all of these defects by providing a construction in which a pressure responsive damper control is utilized which is in direct communication with the combustion chamber and which is subject to the pressure within the combustion chamber and which operates the damper in the proper manner regardless of varying resistance in the smoke passageways of the furnace.

For the purpose of illustrating the application of my invention, I have shown in Fig. 1 a furnace indicated in its entirety by the reference numeral 15. This furnace comprises a return tubular boiler 16 of the so-called locomotive type which is provided with a cylindrical portion 19 integral with a fire box 17. The fire box 17 rests upon an ash pit section 20 which is directly mounted on the floor or foundation 21 on which the boiler is supported. The front wall of the boiler is indicated at 22 and is provided with a fire doorway 23 which communicates with the combustion chamber 24 of the boiler formed within the fire box 17. A door frame 34 surrounds the doorway 23 and is attached to the front wall 22. In the front wall 25 of the ash pit section 20 is pro-

55

vided an ash pit doorway 26 by means of which access may be had to the ash pit 27 within the ash pit section 20. At the front of the boiler 5 is provided a smoke box 30 which has attached to it a smoke pipe 29. This smoke pipe is placed over a nipple 31 on the smoke box 30 and is connected to the chimney in the customary manner. A removable cover 32 gives access to the smoke 10 chamber 33 within said smoke box.

The furnace 15 is shown as provided with a coal stoker 170. This stoker comprises a fire pot 171 disposed within the ash pit 27 and surrounded by a jacket 172 forming an air chamber 173 15 surrounding the fire pot. Air is led into the fire pot 171 through openings 174 in the same. A plate 175 surrounds the jacket 172 and rests on an angle 177 attached to the boiler proper. The coal used with the stoker is stored in a hopper 20 178 and is carried from said hopper to the fire pot 171 by means of a screw conveyor 179 operating in a tube 181. Air under pressure is directed to the chamber 173 by means of a conduit 182 which is connected to a blower 183. The 25 mechanism for operating and controlling the operation of the stoker forming no particular feature of the present invention has not been illustrated or described, though it can be readily comprehended that any construction such as is 30 now well known in the art may be used for the purpose.

In order to prevent cutting a hole in the walls of the fire box 17 which is exceedingly difficult with boilers of the locomotive type for the purpose of subjecting the damper control to the pressure in the combustion chamber 24, the following construction is employed.

Attached to the door frame 34 on the front wall 22 of boiler 15 is a neck 35 which is tubular in form but is open at its ends. This neck is constructed with an upper wall 36, a lower wall 37 and lateral walls 38 giving the said neck a box-like form. The neck 35 is of such dimensions that the same covers the opening of the doorway 23 and forms an extension or continuation thereof. The inner end of the neck 35 is constructed with a flange 39 which overlies the frame 34 and said neck and frame are provided with hinges and a latch, not shown, by means 50 of which the neck may be attached to the frame 34. The outer end of the neck is constructed with a similar flange 41 against which the fire door 43 may be fitted. The neck 35 and door 43 are likewise provided with hinges and a latch 55 not shown by means of which the fire door 43 is hingedly connected to the neck 35 and when open gives access to the combustion chamber 24 for the purpose of removing clinkers and inspecting the fire.

60 The invention embodies a draft regulator indicated in its entirety by the reference numeral 44. This draft regulator includes a damper 45 and a damper control 46 which will now be described in detail.

65 The damper control 46 includes a case 47 which comprises two spaced side walls 48 which are of the shape of a segment of a circle. These walls are parallel to one another and are attached to a substantially radial wall 49 (Fig. 3) which 70 when the invention is installed extends substantially at right angles to the pipe and horizontally when applied to a vertical smoke pipe. The continuation of the wall 49 is provided with a curved or arcuate wall 51 which extends about the arcuate edges of the walls 48 and which ter-

minates in an inwardly turned flange 52 extending toward the center of curvature of the wall 51. The two walls 48 have extensions 53 which overlie the smoke pipe 29 and are clamped about said pipe by means of a bolt 50. The portion 5 of the case 47 opposite the wall 49 is arranged to provide an opening 54 by means of which the interior of the case is subjected to atmospheric pressure.

Between the two walls 48 of case 47 and exteriorly of the smoke pipe 29 is disposed a vane 55. This vane is attached to a shaft 56 by welding or otherwise, which shaft extends through said walls and is journaled therein. The vane 55 is of such dimensions as to closely fit between 15 the two walls 48 and the shaft 56 is disposed at the center of the curvature of the wall 51 so that the vane 55 upon movement of shaft 56 may closely follow the surface of the wall 51. By means of this construction the equivalent of a 20 piston and cylinder is provided, vane 55 serving as the piston, and case 47 as the cylinder.

Within the smoke pipe 29 is disposed the damper 45 which is welded or otherwise secured to a shaft 58. Shaft 58 is journaled in the two extensions 53 and is so arranged as to be disposed across the middle of the smoke pipe. The damper 45 is slightly smaller than the smoke pipe so that the same may move into a position substantially closing said pipe or into a position 30 such as shown in full lines in Fig. 3 in which no obstruction to the flow of flue gases through the smoke pipe results. In order to insert the damper in the smoke pipe 29 a slot 59 is cut in the said smoke pipe which is provided with a 35 notched portion 61 in which the shaft 58 is disposed. This opening is closed by means of an arcuate band 62 which is attached to the extensions 53 of case 47. The wall 49 of said case is constructed with a flange 64 which fits about the 40 band 62. A wall similar to the wall 49 and indicated at 65 is constructed with a similar flange 66 which also fits about said band. Said wall is provided with a flange 67 which lies in the plane of the flange 52 and which in conjunction 45 therewith forms a wall structure bounding the opening 54 and serving as stops which the vane 55 may engage. This wall closes the upper portion of the case 46 and encloses the vane 55 within case 47.

50 In the wall 49 of case 47 is provided a downwardly extending opening 68. A duct 69 provided with a flange 71 is attached to said wall and is in communication with the chamber 72 formed within case 47 through the opening 68. 55 This duct is adapted to be attached to a nipple 73 formed on the wall 36 of neck 35 which nipple is in communication with the doorway 23 leading to the combustion chamber 24. It will thus be seen that the vane 55 is subjected on one 60 side to atmospheric pressure through the opening 54 and on its other side to the pressure within the combustion chamber 24 through opening 68, duct 69 and the doorway 23.

65 The vane 55 operates the damper 45 in the following manner: Attached to the two shafts 56 and 58 are two pulleys 74 and 75. A chain 76 passes over these pulleys and is attached at a certain locality to each thereof. These pulleys are of proper diameter so that when the 70 vane 55 travels throughout its path of movement, the damper 51 will be moved from a position parallel with the smoke pipe 29 to its closing position. The end of shaft 56 to which pulley 74 is attached is bent to provide an arm 176. 75

This arm has adjustably attached to it a counterweight 180 by means of which the vane 55 may be balanced.

Attached to the end of the shaft 56 opposite to that to which the pulley 74 is secured is a segmental pulley 77 best shown in Fig. 1. This pulley has secured to it a chain 78. Chain 78 is pivoted to a beam 79 which in turn is pivoted to a fulcrum 81 secured to case 41. This fulcrum is provided with a number of notches 82. A slideable poise 83 is mounted on the beam 79 and is adapted to engage in any of the notches 82. Beam 79 is formed with an extension 80 on the other side of the fulcrum 81 which permits of moving the poise 83 up to and past the fulcrum 81. By this means the vane 55 may be counter-balanced or over or under counterbalanced so that the device will operate with any suction within the combustion chamber 22.

The operation of the invention is as follows: The poise 83 is adjusted to the proper notch 82 to give the desired draft or suction in the combustion chamber 24. When the draft in the chimney corresponds therewith, the vane and damper occupy the position shown in full lines in Fig. 3. In the event that the draft in the smoke pipe increases and the suction in the combustion chamber 22 correspondingly increases, vane 55 is drawn downwardly in opposition to the poise 83 and the damper 57 is partly closed as shown in dotted lines in Fig. 3. This forms an obstruction in the pipe 29 to the flow of flue gases through the smoke pipe 21 and the suction in the combustion chamber 22 is correspondingly reduced. An adjustment by means of this construction is procured whereby a balance is reached giving the desired suction in the chamber 24.

In Figs. 4 and 5 I have shown a modification of the invention in which the damper control is directly attached to the firing door of the furnace instead of to the smoke pipe. Inasmuch as the construction of the damper control shown in this form of the invention is substantially the same as that illustrated in Figs. 1, 2 and 3, the description of the corresponding parts will not be repeated and the same reference numerals preceded by the digit "1" will be used to designate the corresponding parts.

This form of the invention may be used with any type of furnace and for this reason the furnace has not been shown in detail. The furnace illustrated is designated by the reference numeral 115 and consists of a boiler disposed within a suitable wall structure 118. Within this wall structure is provided an ash pit and a combustion chamber, not shown, to which access may be had through a suitable fire doorway and ash pit doorway closed by a fire door 143 and an ash pit door 128. The flues of the boiler are accessible through another opening closed by a flue door 131. All of these doorways are formed in a front 127 mounted at the forward portion of the wall structure 118 and the doors 143, 128 and 131 are removably attached to said front. At the uppermost portion of the furnace is a smoke pipe 129 which communicates with the smoke chamber of the furnace.

It will be readily comprehended that the form of the invention shown in Figs. 4 and 5 may be equally as well installed on a boiler of the type shown in Fig. 1.

In the form of the invention shown in Fig. 4 the neck 35 is dispensed with and the firing door 143 mounted in the usual manner upon the front 127 of the furnace proper. Case 147 in this form

of the invention is constructed with a neck 84 formed by the walls 149, 148 and 165 which walls are provided with flanges 85 adapted to be bolted to the door 143 by means of bolts 86. The neck 84 provides a passageway 87 which communicates through an opening 88 in the door 143 with the combustion chamber of the boiler. The damper 157 is mounted in the smoke pipe 129 the same as in the other form of the invention, except that the shaft 158 is directly journaled in the walls 10 of the smoke pipe instead of the case 147.

In this form of the invention a complete pulley 89 is used instead of the pulley 77 which is attached to the shaft 156. This pulley has wrapped about it a cable 91 which has attached to one end of it a weight 92. Said cable passes over another pulley 93 secured to a bracket 94 which is attached to the furnace proper. This cable is further wrapped about another pulley 95 secured to shaft 158 for damper 157 and has attached to the extreme end of it another weight 96. It will be readily comprehended that by the proper adjustment of the weights 92 and 96 which are formed of a number of washers indicated at 97 and attached to cotter keys 98, the proper counter balancing of the vane 155 can be procured and operation of the damper brought about the same as with the other form of the invention.

Although I have shown my invention as applied to a certain type of boiler, it can be readily comprehended that the invention may be utilized with a hot air furnace or any type of a furnace or heating plant and oil or gas burning furnaces. Likewise the device may be utilized with a furnace having the smoke pipe at some other locality 35 than that shown.

The advantages of my invention are manifest. The device is made responsive to the draft conditions at the source of the fire instead of at some remote locality which may or may not have draft 40 conditions corresponding to the actual draft conditions at the fire. In this manner proper draft can be had with variable rates of combustion as results in stoker fired furnaces and multiple flame oil burning furnaces. The device is extremely 45 simple in construction and is positive and effective in operation. The invention is not affected by variations in pressure in the smoke pipe which never reach the combustion chamber of the furnace where the regulation is desired. 50

Changes in the specific form of my invention, as herein disclosed, may be made within the scope of what is claimed without departing from the spirit of my invention.

Having described my invention, what I claim 55 as new and desire to protect by Letters Patent is:

1. In a furnace, a fire box providing a combustion chamber, said fire box having a firing doorway therein, a neck open at its ends, said neck being adapted to cover said doorway and extending outwardly from said fire box, said neck having a laterally disposed opening therein, a fire door mounted on said neck and closing the outer end thereof, means forming a passageway for gases of combustion, said passageway communicating with said combustion chamber, a damper in said passageway, a pressure responsive damper control for operating said damper, said control being connected to said neck and being subjected to the pressure within the combustion chamber through 70 the lateral opening in the neck. 65

2. In a furnace, a fire box providing a combustion chamber, said fire box having a firing doorway at the front thereof, a box-like neck having upper, lower and lateral walls and open at its end, 75

said neck being arranged to cover said doorway and extending outwardly therefrom, the upper wall of said neck having an opening therein, a fire door mounted on said neck and closing the outer end thereof, a smoke pipe at the front of said fire box communicating with said combustion chamber, a damper in said smoke pipe, a pressure responsive damper control for operating said damper disposed at the front of the furnace, said control being in communication with said combustion chamber through the opening in said neck.

3. In a furnace, a fire box providing a combustion chamber, said fire box having a firing doorway at the front thereof, a box-like neck having upper, lower and lateral walls and open at its end, said neck being arranged to cover said doorway and extending outwardly therefrom, the upper wall of said neck having an opening therein, a fire door mounted on said neck and closing the outer end thereof, a smoke pipe at the front of said fire box communicating with said com-

bustion chamber, a damper in said smoke pipe, a pressure responsive damper control mounted on said smoke pipe and operating said damper, and a duct between said damper control and the opening in the upper wall of said neck. 5

4. In a furnace, a fire box providing a combustion chamber, said fire box having a firing doorway therein, a member covering said doorway and having two openings therein, a closure movably mounted on said member for opening and closing one of said openings, means forming a passageway for gases of combustion, said passageway communicating with said combustion chamber, a damper in said passageway, a pressure responsive damper control for operating said damper, said control being connected to said member and being subject to the pressure within the combustion chamber through the other of said openings. 10 15

ARTHUR D. COLE. 20
